The ornamental design for a cylindrical track for toy, as shown and described.

DESCRIPTION

FIG. 1 is a perspective view of a cylindrical track for toy showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a perspective view thereof, the broken line showing of the toy vehicles is for illustrative purposes only and forms no part of the claimed design.

The parts of the design seen through the transparent tower form no part of the claimed design.
